UNITED STATES PATENT OFFICE.

DAVID HALL RICE, OF LOWELL, MASSACHUSETTS, ASSIGNOR TO THE CURRIER TELEPHONE BELL COMPANY, OF MASSACHUSETTS.

ELECTRIC CALL.

SPECIFICATION forming part of Letters Patent No. 425,630, dated April 15, 1890.

Application filed February 13, 1882. Serial No. 52,586. (No model.)

To all whom it may concern:

Be it known that I, DAVID HALL RICE, of Lowell, in the county of Middlesex and State of Massachusetts, have invented a new and useful Improvement in Electric Calls, of which the following is a specification.

My invention relates to that class of electric calls patented to Jacob B. Currier, August 30 and December 20, 1881, in Patents No. 246,374 and No. 251,097; and it consists, first, in providing the vibrating caller with a novel make-and-break connection with the electrical circuit, as hereinafter described; secondly, in organizing a series of such callers into a calling-machine by placing them upon a common base and providing it with the necessary circuit-connections attached thereto, and key-boards to put either caller of the series into circuit, as desired; third, in providing said calling-machine with two or more sets of key-boards having duplicate keys connected to the same vibrating circuit-breakers; fourth, in incorporating into said calling-machine in connection with each key-board thereof a self-adjusting rheostat to equalize the resistance of the several circuits leading to the key-boards and enable the calls upon two or more circuits to be made at the same time by the same calling-machine; fifth, in connecting said self-adjusting rheostat with a switch-board and two or more circuits of said Currier bells leading thereto, thereby enabling one rheostat to supply the place of a number which must otherwise be used; sixth, in providing the vibrating circuit-breaker and its tangent screw with an adjusting arrangement, whereby it may be adjusted with relation to its magnet, substantially as hereinafter described.

In the drawings, Figure 1 represents the improved calling-machine, its key-boards, self-adjusting rheostats, switch-board, and three circuits connected therewith and provided with sets of the Currier bells. Fig. 2 shows a side elevation of one of the keys of the key-board. Fig. 3 is a front view of my improvements for adjusting the circuit-breaker and its connected mechanisms, and it also shows my improved contact mechanism for making and breaking the circuit. Fig. 4 is a side view of the same, showing the sup-

porting-post of the contact-screw, partly in section, to display its method of insulation.

G G is the ground of all the circuits. L is the line leading to the caller. A is the base-board of the caller. To its edge is secured the part of the line L extending along its side, as shown. Upon the base A are mounted a series of automatic circuit-breakers b, equal in number to the greatest number of bells 60 upon any one of the circuits. These circuit-breakers operate substantially as shown in my application for Letters Patent thereon, Serial No. 45,955, filed November 16, 1881, but are modified, as hereinafter described. From the 65 respective circuit-breakers short lines connect them to the series of keys K', K², K³, and K⁴, which are attached to the base A. These keys serve to connect the respective circuit-breakers with the line-wire L⁵ when desired. 70

Upon the base-board A is secured an automatic rheostat R of the construction and operation described in the application for a patent of Jacob B. Currier, filed December 15, 1881, Serial No. 47,978. The line L⁵ leads to this 75 rheostat and is secured to the base A. From this rheostat the circuit C' leads outward to the subscribers' stations, two of which S' and S² are shown upon the circuit provided with the Currier bells. The keys K', K², &c., are 80 provided with screw-cups V at their bases, (see Fig. 2,) to which are connected a series of line-wires L', L², L³, and L⁴, leading to the corresponding keys of the separate key-board D. A common line L⁷ for all these keys leads 85 to another of said automatic rheostats R². From this a short line leads to the switch-board E. This switch-board is of well-known construction, and is shown and described in my application for a patent filed October 15, 90 1881, Serial No. 43,846. From this switch-board in the usual manner, as shown, lead the circuits C² and C³ to the subscribers' stations S', S², S³, and S⁴, each of which is provided with a bell of the Currier pattern. 95

It is of course understood that the caller, the key-board, the rheostats, and the switch-board are located at the central office, and that the circuits are at any distance apart and of any desired length. 100

B is the electric battery. The bells as they are used in this arrangement on the different

circuits are so set at all the stations S' as to vibrate in the same time, and at all stations S^2 and S^3 , respectively, in like manner. The vibrating circuit-breakers of the caller are set, respectively, to ring the bells at the different stations—that is, K' rings S' , K^2 rings S^2 , K^3 rings S^3 , and K^4 rings S^4 . Now, let it be desired with this single caller to ring either two bells at different numbered stations on different circuits or at the same numbered stations on different circuits by two different operators in the central office at the same time. This is known to be frequently required in large telephone-offices, and is indeed indispensable to their business success.

The Currier automatic rheostat, as is well known and demonstrated by its daily use, allows only the amount of electric current for which it is set or gaged per bell to go to line and then automatically interposes resistance to the remainder. This peculiar quality of it acts with new and advantageous effect in the arrangement shown. Suppose circuits C' and C^3 were connected directly to their key-boards without the rheostats. Then it is evident that when key K^4 of the key-board D and the same or any other key of the caller were pressed down simultaneously the electric current would all pass over circuit C' , it being the shortest and with least resistance, and circuit C^3 would get none of it and its bell at S^4 would not ring. When, however, the Currier rheostat is used, any excess of electric current tending to flow over C' beyond what is needed is automatically stopped by the rheostat and turned back to supply circuit C^3 , and each circuit gets sufficient to ring any bells on each at the same time, and only the excess of battery-power, if any, is acted upon by the rheostats. If circuit C^2 be switched in instead of C^3 , the rheostat R^2 will at once regulate the amount of electric current per bell going over the circuit, the same as for circuit C^3 . By my arrangement, therefore, of key-boards, rheostats, and circuits I am able to ring any bell on one circuit at the same time as any one on another, and by one or more operators in different places at the same time. I am also able to employ the excess of battery-power above what is needed for any particular circuit to run as many additional circuits as may be required up to the capacity of the battery without waste or loss of the same, which would not be possible with an ordinary rheostat. For instance, suppose an ordinary rheostat is used to prevent an undue excess of battery-power from interfering with the proper operation of the bells on line C' . When the line C^3 is connected with the battery, the resistance of the common rheostat in line C' would send the electric current over line C^3 , and the bells on line C' would fail to ring at the same time as those on line C^3 . To avoid this difficulty and operate bells upon either one or two or three circuits at pleasure, as described, with common rheostats is impos-

sible, because the rheostat upon circuit C' to operate it alone must always equal in resistance the excess of battery-power above what is necessary to operate the calls upon that circuit, and if the calls of any other circuit were attempted to be operated at the same time by making the resistance of both circuits alike, the sum of the resistance of both circuits would be greater than the battery-power and neither would be operated. The separate key-board D is also an important improvement in connection with the caller, for it can be set at any distance therefrom and several of them may be attached to as many different tables at the central office and at any convenient distance from the caller. This enables one caller to suffice for the largest exchange when a Currier automatic rheostat is used with each key-board, because any circuit can be switched on to any key-board at pleasure, as is now done, and the work of the central office thus apportioned among its operators.

By attaching all the circuit-breakers b to a single base A and providing it with attached lines L , L^5 , and keys, if desired, or screw-cups for one or more sets of lines L' , L^2 , L^3 , and L^4 , leading to one or more key-boards, I organize the separate circuit-breakers and their attachments into a single instrument capable of being immediately placed in connection with the system of any telephone-exchange without trouble or delay which would otherwise occur. This is of great advantage.

My improvements in the vibrating circuit-breaker of the caller are shown in detail in Figs. 3 and 4, and in general in Fig. 1.

Great trouble has heretofore been experienced in so constructing a circuit-breaker to be operated by the electric current going to line that it would be set in motion by a slight current sufficiently to be certain to operate and at the same time preserve its synchronous vibration accurately enough to be certain to set in motion the vibrating striker sought to be operated at a distant station. One method of accomplishing this result has been shown in a former application I have made, wherein the tangent screw forming the electrical contact for the circuit-breaker to make and break against was made the center about which the circuit-breaker moved during part of its stroke. It was found that whenever an auxiliary light spring was used to make the electrical contact being attached to the circuit-breaker, and was placed in the ordinary manner so as to press against the fixed contact-point, or when the auxiliary light spring was attached to the fixed point and made to bear upon a contact attached to the circuit-breaker, the consequent tension which it gave to the circuit-breaker spring, when sufficient pressure was applied to make a good electrical contact, prevented the circuit-breaker from being put in vibration so as to make and break the circuit by means of the electric current of normal power passing

over it. The reason why the method of overcoming this difficulty last above mentioned accomplished it was that the contact-point was placed so near to the post holding the 5 vibrator-spring that a large part of the spring between it and the armature was not put in tension by its pressure, and the electric current could consequently set the circuit-breaker in vibration. The tension which the 10 contact-screw did exert upon the circuit-breaker, however, rendered its proper adjustment a matter of extreme nicety, and in addition, since it must be on the opposite side of the circuit-breaker from its magnet, it 15 caused the circuit-breaker to make the longest portion of its beat toward the magnet, thus compelling the use of a very powerful magnet, so as to enable it to be set at a sufficient distance from the circuit-breaker and 20 start the latter in movement. It is to remedy these inconveniences and produce an improved result that my present improvement is devised.

In the drawings, Figs. 3, 4, and 1, *m m* is 25 the magnet. *n* is the vibrating armature carrying the circuit-breaker. *q* is the tangent screw. *p* is the light auxiliary spring which forms the electrical contact to be made and broken by the circuit-breaker. The circuit 30 is formed through screw *q*, upon the contact-point of which the auxiliary spring *p* bears, forming the electrical contact; thence it leads through spring *p*, thence through post *o*, in which the circuit-breaker spring is fixed, 35 thence from the metallic base of said post through magnet *m* to the key of the caller or key-board. The screw *q* is supported by a post *r*, which is secured by insulating material to the metallic base of the post *o*, as hereinafter described. The spring *p* is placed in 40 such a direction and so bears upon its contact-point of the screw *q* as to leave the spring of the circuit-breaker *n* substantially without tension at the same time it forms the 45 chord of the arc having the gripping-point of the post *o* upon the circuit-breaker spring as a center and passing through the contact-point of the screw *q*. This construction not only leaves the spring of the circuit-breaker 50 *n* in the most favorable position to be set in operation by the first impulses of the electric current, but it also causes the spring *p* to instantaneously leave the contact-point of its screw *q* when the circuit-breaker *n* moves 55 from its normal position of rest toward the magnet, while when the circuit-breaker moves from said position away from the magnet it is but very slightly opposed by the tension of the spring *p*, owing to the surface of the latter sliding along upon its screw contact-point. It will thus be seen that while I insure the 60 most favorable position of the circuit-breaker to be set in motion by faint electric currents, I also insure the best breaking of the circuit 65 during the movement of the circuit-breaker in one direction and a make of the circuit during its movement in the other direction,

which does not perceptibly interfere with the synchronism of its vibration with any striker at a distant station which it is used to operate. The result is that the capacity of the circuit-breaker to allow a great variation in the electric current by which it and the bell-strikers are to be operated is attained, and any variation of current which will permit of 70 the bell-strikers being operated will also set in operation automatically the vibrating circuit-breaker. It is upon these two qualities that my improvement depends—*i.e.*, that the auxiliary spring *p*, when given sufficient tension to make a good electrical contact, shall 75 leave the circuit-breaker spring substantially without tension, which would prevent its being set in motion effectively by the electrical current, and at the same time the spring *p* shall 80 so bear upon its contact-point as to allow the latter to slide upon its surface when the contact is made by the movement of the circuit-breaker in one direction and leave its surface when the circuit-breaker moves in the other 85 direction. I am thus able to accomplish what I believe has not before been done, which is to make a practical circuit-breaker operated automatically by the electrical current to be broken with perfect synchronism of movement under all the variations of such current which occur in its practical daily use over 90 long circuits in the open air.

I will now describe my apparatus for adjusting the circuit-breaker *n* and its contact-screw *q* with relation to the magnet *m*. *F* is a metallic casting of the usual form, screwed to the base *A* by the screw *u*. To its upright arm the magnet is secured by the screw *w*. Upon this base is secured the swinging arm *t* 105 by the screw *u*², upon which it is pivoted. A slot at its free end with the clamp-screw *u*³ allows it to be swung around the pivot-screw *u*² and fastened in any desired position, which movement adjusts the circuit-breaker *n* to or 110 from its magnet. In order to insulate the post *r*, which carries the screw *q*, and at the same time support the post upon the swinging arm *t*, I adopt the following construction: Through the swinging arm *t* a hole is 115 made, which receives a washer of vulcanite *v*', Fig. 4, shouldered as shown. Through the center of this washer *v*' passes a screw *u*⁴, having a large metallic washer *v*⁵ between its head and the vulcanite to give it a broad 120 bearing-surface upon the latter. On top of the swinging arm *t* is placed another piece of vulcanite insulating material *v*², and on top of this a metallic plate *t*², which bears only upon the vulcanite beneath it. The vulcanite *v*² and plate *t*² have each a hole through them large enough to receive the screw *u*⁴ and allow the latter to pass freely up into the post *r*, where the screw takes into a corresponding thread in a hole in the post. It 130 will be seen that when the screw *u*⁴ is set up solidly the post *r* will be rigidly secured to the swinging arm *t* while being insulated from it. It is obviously a great advantage

to have the screw q thus supported and adjusted simultaneously with the vibrating circuit-breaker, because the latter can thus be adjusted with relation to its magnet without disturbing the adjustment of its attached spring p and the screw q .

Instead of having p in the form of an elastic spring and the screw q rigidly fixed, p may be made rigid and the screw q held 10 against it by elastic pressure, if desired, which can be accomplished by giving the proper elasticity to the vulcanite pieces v' and v^2 , or in any other suitable manner.

In order to cause the screw q to be carried 15 forward accurately against the spring p to form a contact and to secure it in position when properly adjusted, the post r is so made that a screw-thread is cut in one branch of its bifurcated end r' , while the other 20 branch has a longitudinal slot cut down to the passage for the screw q , as shown in Fig. 3, and a grip-screw w^6 is carried through across this slot and above the screw q , as shown. By setting up the screw w^6 this 25 branch of the bifurcated post is made to clamp the screw q and hold it firmly in any desired position without disturbing its adjustment against the spring p .

What I claim as new and of my invention 30 is—

1. In combination with the base-board A , two or more attached circuit-breakers b , and the attached circuit L , and connecting short circuits leading from the circuit-breakers b 35 to a series of keys, the whole being organized into a completed calling-machine and adapted to sound different alarms upon an electrical circuit connected therewith, substantially as described.

2. In combination with the calling-machine A' , organized substantially as described, the independent key-board D , connected to the circuit-breakers of such calling-machine, substantially as described.

3. In combination with a single circuit-breaker b , two or more separate keys K^4 in electrical connection therewith and two or more corresponding circuits $L^5 L^7$ in connection with said keys, respectively, substantially as described.

4. In combination with a single circuit-breaker b , two independent keys K^4 , electrically connected therewith, two corresponding electrical circuits $L^5 L^7$, respectively in 55 connection with said keys, and two rheostats $R R^2$, respectively connected with said circuits, substantially as described.

5. In combination with a single circuit-breaker b , the key K^4 , electrically connected 60 therewith, the circuit L^7 , the rheostat R^2 , the switch E , and the electrical circuits $C^2 C^3$, substantially as described.

6. In combination with the magnet m , the swinging arm t and circuit-breaker n , attached 65 thereto, substantially as described.

7. In combination with the magnet m , the

swinging arm t , carrying thereon the circuit-breaker n , and the screw q , substantially as described.

8. In combination with the swinging arm t , 70 the post r and screw q , placed in circuit and insulated from the swinging arm by means of the shouldered non-conducting washer v' and non-conducting plate v^2 , substantially as described.

9. In combination with the screw q and contact-spring p , in electrical connection therewith, the screw w^6 and slotted post r , substantially as described.

10. The combination of the magnet m , its 80 armature n , suspended upon a support upon which it vibrates to and fro, the contact-spring p , attached to the armature and having its contact-surface lying approximately in the direction of the line of its vibratory 85 movement, the contact-point arranged to bear upon said surface of the contact-spring transversely to its line of movement to and fro during part of the same, and an electric circuit leading through said contact-point, contact-spring, armature, and magnet, and grounded on each side of the same, substantially as described.

11. The combination of the magnet m , its 90 armature n , suspended upon a support in position to be vibrated by an electric current passing through the magnet, the electric conductor L^6 , connected to said armature and grounded, a vibrating alarm-striker on the latter circuit, arranged to respond to its magnet synchronously with armature n , an electrical contact-point connected to ground by the electric conductor L , a source of electric energy upon the latter, and the spring p , projecting from the armature n past said contact-point in a direction parallel, or approximately 100 so, to its plane of movement, whereby its contact-surface is adapted to reciprocate bodily to and fro upon said contact-point and to leave the same when the armature is vibrated, substantially as described.

12. The combination of the magnet m , its 110 armature n , suspended upon a support in position to be vibrated by an electric current passing through the magnet, the electric conductor L^6 , connected to said armature and leading to ground, an electric contact-point connected to ground by the electric conductor L , a source of electric energy upon the latter, and the spring p , projecting from the armature n past said contact-point in a direction parallel, or approximately so, to its plane of 120 movement, whereby its contact-surface is adapted to reciprocate bodily to and fro upon said contact-point and to leave the same when the armature is vibrated, substantially as described.
